REFRIGERATOR CABINET INCLUDING
MEANS FOR PREVENTING CONDENSA-
TIONWalter Peglow, Cazenovia, N. Y., assignor to Car-
rier Corporation, Syracuse, N. Y., a corporation
of Delaware

Application September 7, 1945, Serial No. 614,928

8 Claims. (Cl. 62—89)

1

This invention relates to refrigerator cabinets and more particularly to refrigerator cabinets such as home freezers including a center stile against which doors of the cabinet seal and which include means for preventing condensation at the exposed surface of the center stile.

Heretofore, various manufacturers have presented cabinet structures in which the door extends over the full width of the cabinet. When such design was applied to cabinets with double doors it was not generally successful. If the doors are placed substantially in contact at the center of the cabinet, the center stile, against which the doors seal, collects condensate or shows signs of "sweating" when the structure is in use. This problem becomes greater if this flush door type of cabinet is employed as a home freezer due to the low interior temperature maintained in the cabinet. Various structures have been presented in an effort to solve this problem of condensate collection at the center stile. None has been particularly successful. The structures proposed were expensive, inefficient, unsatisfactory and, as a matter of fact, failed to solve the problem.

The chief object of this invention is to provide a refrigeration cabinet which includes means for obviating the collection of condensate or "sweating" at the exposed surface of the center stile.

An object of the invention is to provide a refrigeration cabinet of the flush door type embodying in its structure means which prevent the collection of condensate at the center stile.

A further object is to provide a refrigeration cabinet in which warmed air from the machine compartment is passed over the exposed surfaces of the center stile to warm and dry the exposed stile surface including the door edges thus preventing condensation of moisture from the ambient air at such surfaces.

A still further object is to provide a novel design of refrigeration cabinet of the flush door type embodying means for maintaining the exterior exposed surface of the center stile in a dry, warm condition without impairing to any substantial extent the temperature of the cabinet interior. Other objects of my invention will be readily perceived from the following description.

This invention relates to a refrigeration cabinet which comprises in combination a frame including a stile, a portion of the exterior surface of the stile being exposed to ambient air, said frame forming a storage compartment, said compartment being adapted to be maintained at a temperature lower than the temperature of the am-

2

bient air, a plurality of doors closing said storage compartment, the doors having recesses in their adjoining edges and being disposed in slightly spaced apart relation (having their edges substantially in contact or substantially flush when the doors are closed), the recesses forming a channel or flue extending along the stile, and means for passing warmed air at a temperature higher than the temperature of ambient air into said channel thereby preventing condensation of moisture from the ambient air at the exposed surface of the stile when the cabinet is in use.

The attached drawing illustrates a preferred embodiment of my invention, in which:

15 Figure 1 is a view in elevation of the refrigeration cabinet of my invention;

Figure 2 is a plan view of the cabinet shown in Figure 1;

20 Figure 3 is a sectional view taken along the line 3—3 of Figure 1; and

Figure 4 is a sectional view taken along the line 4—4 of Figure 1.

25 Referring to the drawing, there is shown a refrigeration cabinet 2 of the flush door type including a storage compartment 3 and a machine compartment 4 for the accommodation of compressor and associated elements 5 of a refrigeration system. The storage compartment 3 is disposed above the machine compartment 4.

30 As is customary in cabinets of this type, the compressor, condenser, driving mechanism, etc., is placed in the machine compartment and a suitable heat exchanger or evaporator is placed in the storage compartment and connected to the condenser by a suitable liquid conduit. These elements per se form no part of my invention and consequently are not shown in detail.

35 The cabinet 2 includes metal or wood longitudinal frame members 6 at its corners and connecting elements are provided between the various corner members to form the whole into a unitary frame for the cabinet. An exterior wall 7 having any suitable decorative surface conceals the frame. Interiorly of the frame there is provided

40 an interior liner or wall 8 which forms the storage compartment 3. Insulation 9 of any suitable type, for example, cork board, mineral wool, fiberboard or the like, is interposed between walls 7 and 8 surrounding compartment 3 on all sides.

45 A stile or mullion 10 forms a portion of the unitary frame extending perpendicularly of the storage compartment. Stile 10 divides one side of the storage compartment into a plurality of openings to permit access to the compartment for placement and removal of stored foodstuffs,

50

for example. The openings in the compartment 3 are closed by doors 11 which are suspended from supports 6 of the frame by hinges 12. The doors 11 are substantially flush at the center stile 10; that is, the exterior surfaces of doors 11 are slightly spaced apart but present the appearance of being substantially in contact with one another. Gaskets 13 are interposed between the doors 11 and the walls of the cabinet 2 thus securely sealing the storage compartment 3 and preventing ingress of ambient air.

The adjacent edges 14 and 14' of doors 11 are formed with recesses 15 and 15' which form side walls of a channel or flue 16 extending substantially perpendicularly of the cabinet 2 at the center stile 10; the exposed exterior surface of stile 10 forms the rear wall of channel 16. It will be noted the gaskets 13 securely seal channel 16 from the interior of storage compartment 3.

Machine compartment 4 may be closed in any desired manner, preferably, by a panel 17 hinged across the front thereof. An opening 18 is provided in the upper flange of panel 17 to permit warmed air from the compressor element 5 of the refrigeration unit to pass through opening 18 into channel 16; the warmed air rises in channel 16 to the top of the refrigeration compartment. Such warmed air dries the edges 14 and 14' of doors 11 and the exposed surface of stile 10 thus preventing condensation of moisture from the ambient air at the exposed surface of stile 10. In some cases, baffles 19 of any suitable construction may be provided in the machine compartment to guide warmed air from compressor and associated elements 5 to opening 18 whence it passes into and rises in channel 16.

My invention provides a simple economical cabinet construction which obviates the collection of condensate at the exposed surface of the center stile. The construction so provided retains the appearance of flush door types of structures and prevents condensation at the center stile without increasing the cost of the structure. My invention permits the desired appearance of flush-door types of structures to be retained while eliminating a disadvantage inherent in such structures without increase in the cost of manufacture or operation. The invention is particularly adapted for domestic refrigerator and home freezer structures.

"Sweating" of the center stile is obviated and the exposed surface thereof is maintained dry and warm.

While I have described a preferred embodiment of my invention, it will be understood my invention is not limited thereto since it may be otherwise embodied within the scope of the following claims.

I claim:

1. In a refrigeration cabinet, the combination of a frame including a stile, a portion of the surface of said stile being exposed to ambient air, said frame forming a compartment for the reception of elements of a refrigeration unit and a storage compartment, doors closing said storage compartment, said doors being disposed in spaced relation to form side walls of a channel extending along the stile, and means for passing warmed air from the bottom unit compartment to said channel, the warmed air passing upwardly in said channel thereby obviating collection of moisture at the exposed surface of the stile when the cabinet is in use.

2. In a refrigeration cabinet, the combination of a frame including a stile, a portion of the surface of said stile being exposed to ambient air, said frame forming a compartment for the reception of elements of a refrigeration unit and a storage compartment disposed above the unit compartment, said storage compartment being adapted to be maintained at a lower temperature than the ambient air, doors suspended from said frame closing said storage compartment, said doors having their adjacent edges, substantially in contact with one another, a recess in at least one of said substantially contacting edges forming a channel extending substantially perpendicularly of the cabinet, the stile forming the rear wall of the channel, and means for passing warmed air from the bottom compartment to said channel thereby obviating collection of moisture at the exposed surface of the stile when the cabinet is in use.

3. A refrigeration cabinet according to claim 2 in which baffles are provided in the unit compartment to direct warmed air into the channel.

4. In a refrigeration cabinet, the combination of a frame including a stile, a portion of the surface of the stile being exposed to ambient air, said frame forming a storage compartment, said compartment being adapted to be maintained at a temperature lower than the temperature of the ambient air, a plurality of doors closing said storage compartment, the edges of said doors being disposed in spaced relation to form a channel extending along the exposed surface of the stile, and means for directing air at a temperature higher than the temperature of ambient air through said channel thereby obviating collection of moisture at the exposed surface of the stile when the cabinet is in use.

5. In a refrigeration cabinet, the combination of a frame including a stile, a portion of the surface of the stile being exposed to ambient air, said frame forming a storage compartment, insulation material disposed about said storage compartment, said compartment being adapted to be maintained at a temperature lower than the temperature of the ambient air, said compartment having openings therein on opposite sides of said stile to permit access to the compartment, doors closing said openings, said doors having their adjacent edges substantially in contact with one another, at least one of said doors having a recess in its adjacent edge to form a channel extending substantially perpendicularly of said stile, said stile forming the rear wall of said channel, and means for passing air at a temperature higher than the temperature of ambient air into said channel thereby obviating "sweating" of the exposed portion of the stile when the cabinet is in use.

6. In a refrigeration cabinet, the combination of a frame including a stile, a portion of the surface of the stile being exposed to ambient air, said frame forming a top storage compartment and a bottom compartment for the reception of elements of a refrigeration unit, said storage compartment being adapted to be maintained at a temperature lower than the temperature of the ambient air, insulation material disposed about said storage compartment, said compartment having openings therein on opposite sides of said stile to permit access to said compartment, doors closing said openings, said doors having their adjacent edges in substantially contacting relation, recesses in said edges cooperating to form side walls of a channel, the stile forming

the rear wall of the channel, said bottom compartment having an opening therein leading to said channel, and a refrigeration element in said bottom compartment adapted to warm air whereby air so warmed passes through said opening into said channel and upwardly therein along the exposed surface of the stile to maintain such surface in a dry condition.

7. A cabinet structure according to claim 6 in which sealing means are disposed between the doors and the stile to prevent ingress of warmed air into the storage compartment.

8. A cabinet structure according to claim 6 in which a baffle is provided to direct air warmed by

said element through the opening in the bottom panel into the channel.
